UNITED STATES PATENT OFFICE

165,322

STENOGRAPHER'S CHAIR

John S. Burdick, North Muskegon, Mich., assignor
to The Shaw-Walker Company, Muskegon,
Mich., a corporation of Michigan

Application September 7, 1950, Serial No. 12,086

Term of patent 14 years

(Cl. D15—1)

To all whom it may concern:

Be it known that I, John S. Burdick, a citizen of the United States, residing at North Muskegon, in the county of Muskegon, State of Michigan, have invented a new, original, and ornamental Design for a Stenographer's Chair, of which the following is a specification, reference being made to the accompanying drawing, forming part thereof, wherein:

Figure 1 is a face view of a stenographer's chair, showing my new design;

Figure 2 is a side view thereof;

Figure 3 is a three-quarter perspective view thereof; and

Figure 4 is a rear view thereof.

I claim:

The ornamental design for a stenographer's chair, as shown.

JOHN S. BURDICK.
